UNITED STATES PATENT OFFICE.

LOUIS A. DOURSON, OF CINCINNATI, OHIO, ASSIGNOR TO THE AMERICAN OIL PUMP & TANK CO., OF CINCINNATI, OHIO, A CORPORATION OF OHIO.

DOUBLE-CYLINDER DOUBLE-ACTING PUMP.

Application filed March 31, 1927. Serial No. 179,903.

My invention relates to double acting, double cylinder, reciprocating piston pumps.

Similar machined castings forming the pump body, looking toward the side which is joined to the other casting.

Such pumps are well adapted for use in visible dispensing apparatus for gasoline, in pumping the gasoline from the underground storage tank to the glass bowl at the top. Their compactness permits their being mounted in the housing of such apparatus.

Referring now to the drawings, the pump body is made up of two generally similar castings A and B. Casting A carries a connection a for the suction pipe (not shown)

One object of my invention is to provide a highly concentrated, inexpensive pump of the continuous flow type the operation of which will not be interfered with by small particles of grit and sediment.

55 Casting A carries a connection a^1 for the discharge pipe (not shown), and has a plugged opening a^2 thru which water and sediment may be

Another object of my invention is to provide an apparatus that can be used to pump liquid continuously by continuous rotation of the crank in either direction, at the option of the user. A left handed person can use it with the same facility as a right-handed person.

55 Within the outer side of the casting A is formed a cylindrical chamber a^3 preferably lined with a thin brass tube a^4 . The inner

Another object is to provide a pump that is easily assembled and will have all necessary accessibility for cleaning the valves or for making other repairs.

60 The inner side of the casting A is generally flat in shape having an encircling raised portion a^5 . It also has a central rib a^7 which extends

Another object of this invention is to have all working parts protected from the weather by the casing and run in the liquid pumped, rendering other provision for lubrication unnecessary.

65 It also has a central rib a^7 which extends lengthwise centrally of this flat portion and at its ends unites with the opposite sides of the encircling raised portion a^5 . Raised

The particular embodiment of my invention selected for illustration, is a gasoline pump shown in the accompanying drawings, in which:—

70 Raised portions a^5 and a^7 have their seating surfaces in the same plane and a cutout gasket g^1 of the same general form as said seating

Figure 1, is a longitudinal section on the axis of the crank shaft and on the line 1—1 of Fig. 2 as though shown there in full,

75 It also has a central rib a^7 which extends lengthwise centrally of this flat portion and at its ends unites with the opposite sides of the encircling raised portion a^5 . Raised

Fig. 2, is a cross section on the line 2—2 of Figure 1,

75 Bosses a^8 on the surface of the outer side of the casting A are tapped to receive cap

Fig. 3, is a cross section on the line 3—3 of Figure 1,

75 Screws (not shown), by which the pump is secured to the housing, (not shown) in

Fig. 4, is a cross section on the line 4—4 of Fig. 6, the body castings only being shown,

75 which it is placed.

Fig. 5, is a cross section on the line 5—5 of Fig. 6, the body castings only being shown,

80 Generally co-axial with the cylinder a^3 at the top of the casting A is an opening a^9 for purposes of assembly, which opening is

Fig. 6, is an elevation of the pump on the side opposite the crank, and

85 tapped and closed by a screw plug a^{10} . The bottom cylinder head is formed of a casting

Fig. 7, is a perspective of one of the two

85 a^{11} secured to the casting A with gasket g between, by cap screws a^{14} or in any other

convenient manner; and carries a guiding portion a^{12} co-axial with the cylinder and bored to receive a depending prolongation

85 p of the piston P. A screw plug a^{13} is used to close the bottom of the guide a^{12} , and may

90 be removed for drainage. The piston P is of any suitable double acting type, and the connecting rod p^1 has a cap p^2 secured in position by cap screws p^3 in the usual manner.

95 On the inner side of the casting A are two longitudinal depressions a^{15} , a^{16} , one on

either side of the rib a^7 . Near the bottom

portion of each of these depressions the casting A is bored to receive a valve seat and spring closed valve mechanism. One of these valves is a suction valve designated as SV and the other a discharge valve designated as DV. The valve seat, disc, stem and spring of any convenient form are assembled complete before being placed in the opening bored to receive them. Near the upper end 10 of these depressions a^{15} , a^{16} the casting is bored to receive two valves similar to the ones near the lower ends of the depressions. Both the valves in one depression will be suction valves and both those in the other 15 depression discharge valves.

The casting designated as B has a cylinder b^3 similar to a^3 with a brass lining tube b^4 similar to a^4 ; has a raised portion b^5 similar to a^5 , a rib b^7 similar to a^7 , an opening b^9 similar to a^9 with a cap b^{10} similar to a^{10} . It also has a bottom cylinder head b^{11} similar to a^{11} , with guiding portion b^{12} similar to a^{12} , a screw plug b^{13} similar to a^{13} , and cap screws b^{14} similar to a^{14} . It also has longitudinal 20 depressions b^{15} similar to a^{15} , and b^{16} similar to a^{16} , and suction valves SV and discharge valves DV similar in all respects to those heretofore described installed in the casting A. When the flat portions of the castings 30 A and B are placed together the surface of a^5 will contact with the surface of b^5 and the surface of a^7 with the surface of b^7 , with the gasket g^1 between them. The depressions a^{15} and b^{15} will together form the suction 35 chamber and the depressions a^{16} and b^{16} will together form the discharge chamber. It will be seen that there will be four suction valves opening inwardly from the suction chamber and four discharge valves opening 40 outwardly into the discharge chamber. The two castings A and B are secured together by suitable cap screws s .

The suction chamber connects at its bottom thru the appropriate suction valve and 45 passage a^{20} with the bottom of the cylinder a^3 in the casting A, and likewise with the bottom of the cylinder b^3 thru passage b^{20} in the casting B. At its top the suction 50 chamber connects above the crank shaft and the cylinder a^3 thru the appropriate suction valve with a chamber a^{19} in the casting A; and similarly with the chamber b^{19} above the cylinder b^3 in the casting B. Likewise 55 the discharge chamber connects thru its appropriate discharge valve and passage a^{21} with the bottom of the cylinder a^3 in the casting A and likewise with the bottom of the cylinder b^3 thru passage b^{21} in the casting B. At the top of the discharge chamber the 60 discharge valves make fluid connection with the chamber a^{19} in the casting A and b^{19} in the casting B.

The crank shaft is formed of four parts 65 C, C¹, C², C³ and passes thru the pump from side to side substantially thru both castings

A and B, having suitable boss a^{17} bored and provided with plug a^{18} on one side and boss b^{17} , provided with suitable packing nut, gland and packing b^{18} on the crank end. The crank handle c with handle knob c^1 70 is rotatively secured to the section C of the crank shaft. A crank c^2 having crank pin integral with it, is bored to receive the section C of the crank on one side and the section C¹ of the crank on the other side and has 75 set screws c^3 and lock nuts c^4 to hold the parts rigidly in position. The portions C, C¹ of the crank shaft are placed in position when the entire mechanism is assembled in the casting B. In like manner the sections 80 C² and C³ of the crank shaft are assembled with the crank c^5 in the casting A similar in all respects to the sections C and C¹ of the crank shaft and the crank c^2 in the casting B. When the two sections A and B with all 85 the mechanism in each are placed together, the tongue c^6 on the section C² fits into the groove c^7 on the section C¹ of the crank shaft, making the whole crank shaft rotatable thru the handle c . The crank c^2 is of 90 course set at right angles to the crank c^5 , as shown in Fig. 1.

The operation of the pump is as follows:

The fluid suction passage a being always open to the source of supply and the fluid discharge passage a^1 being always open to discharge fluid from the pump, and the pistons being in the positions shown in Fig. 1 with all chambers and passages full of liquid, rotation of the handle c in either direction 100 will raise the piston P in the casting B causing liquid to enter the space under said piston thru the appropriate suction valve and passage b^{20} from the suction chamber a^{15} , b^{15} . At the same time liquid above this piston will be forced out of the chamber b^{19} thru the appropriate discharge valve and the discharge passage a^{16} , b^{16} thru the discharge outlet a^1 to service.

At the same time and assuming that the 110 direction of rotation selected will cause the piston in the casting A to descend, liquid will flow into the chamber a^{19} from the suction chamber a^{15} , b^{15} above the piston, and below the piston will flow into the discharge chamber a^{16} , b^{16} thru the discharge passage a^{21} , and then thru outlet a^1 to service. As the cranks c^2 , c^5 are set at an angle to each other of 90 degrees the continuous operation of the 115 pump is obvious. When any particular suction valve is open the discharge valve communicating with the same end of the cylinder is closed.

It will be obvious that when the cap screws 120 are removed and the part B removed from its contact with part A, all valves are readily accessible and that in so separating the parts A and B, neither the suction nor discharge pipe connections need be disturbed.

I do not wish to limit myself to the precise 125

form of mechanism shown and described but claim as within the scope of my invention all devices readable on the claims finally allowed.

5 I claim as my invention and desire to secure by Letters Patent of the United States:

1. A double acting two cylinder reciprocating piston pump, having in combination

two parts each containing a cylinder, means 10 for securing said parts to each other to form a pump body, channels in the so attached side of each said part so that when said parts are united a suction chamber and a discharge chamber will be formed by said channels, a fluid passage connecting each cylinder at each of its ends with the suction chamber, a valve in each of said passages opening away from the suction chamber, a fluid passage connecting each cylinder at each of its 15 ends with the discharge chamber, a valve in each of said passages opening toward the discharge chamber, a suction inlet connected with said suction chamber and a discharge outlet connected with said discharge chamber, a double acting piston for each cylinder and means for reciprocating said pistons.

2. A double acting two cylinder reciprocating piston pump, having in combination two parts each containing a cylinder, means

30 for securing said parts to each other to form a pump body, channels in the so attached side of each said part so that when said parts are united a suction chamber and a discharge chamber will be formed by said channels, a fluid passage connecting each cylinder at each of its ends with the suction chamber, a spring closed valve in each of said passages opening 35 away from the suction chamber, a fluid passage connecting each cylinder at each of its ends with the discharge chamber, a spring closed valve in each of said passages opening toward the discharge chamber, a fluid

40 passage connecting the exterior of the pump with the suction chamber, a fluid passage connecting the discharge chamber with the exterior of the pump, a double acting piston for each cylinder, a connecting rod for each piston and unitary means for reciprocating said pistons, thru said connecting rods.

35 3. A double acting two cylinder reciprocating piston pump, having in combination two castings of generally semicylindrical shape each containing a cylinder, means for

45 securing the flat sides of said castings to each other to form a pump body, the flat side of each casting channelled so that when united said castings will form a suction chamber and a discharge chamber, a fluid

50 passage connecting each cylinder at each of its ends with the suction chamber, a valve in each of said passages opening away from the suction chamber, a fluid passage connecting each cylinder at each of its ends with the discharge chamber, a valve in each of said

55 passages opening toward the discharge chamber, a suction inlet connected with said suction chamber and a discharge outlet connected with said discharge chamber, a double acting piston for each cylinder, means for reciprocating said piston thru said connecting rods.

60 4. A double acting two cylinder reciprocating piston pump, having in combination two castings of generally semicylindrical shape each containing a cylinder, means for

65 securing the flat sides of said castings to each other to form a pump body, the flat side of each casting channelled so that when united said castings will form a suction chamber and a discharge chamber, a fluid

70 passage connecting each cylinder at each of its ends with the suction chamber, a valve in each of said passages opening away from the suction chamber, a fluid passage connecting each cylinder at each of its ends with the discharge chamber, a valve in each of said

75 passages opening toward the discharge chamber, a suction inlet connected with said suction chamber and a discharge outlet connected with said discharge chamber, a double acting piston for each cylinder and means for reciprocating said pistons.

76 5. A double acting two cylinder reciprocating piston pump, having in combination two castings of generally semicylindrical shape each containing a cylinder, means for

80 securing the flat sides of said castings to each other to form a pump body, the flat side of each casting channelled so that when united said castings will form a suction chamber and a discharge chamber, a fluid

85 passage connecting each cylinder at each of its ends with the suction chamber, a valve in each of said passages opening away from the suction chamber, a fluid passage connecting each cylinder at each of its ends with the discharge chamber, a valve in each of said

90 passages opening toward the discharge chamber, a suction inlet connected with said suction chamber and a discharge outlet connected with said discharge chamber, a double acting piston for each cylinder, a connecting rod for each piston and unitary means for reciprocating said pistons, thru said connecting rods.

95 6. A double acting two cylinder reciprocating piston pump, having in combination two castings of generally semicylindrical shape each containing a cylinder, means for

100 securing the flat sides of said castings to each other to form a pump body, the flat side of each casting channelled so that when united said castings will form a suction chamber and a discharge chamber, a fluid

105 passage connecting each cylinder at each of its ends with the suction chamber, a valve in each of said passages opening away from the suction chamber, a fluid passage connecting each cylinder at each of its ends with the discharge chamber, a valve in each of said

110 passages opening toward the discharge chamber, a suction inlet connected with said suction chamber and a discharge outlet connected with said discharge chamber, a double acting piston for each cylinder and means for reciprocating said pistons.

115 7. A double acting two cylinder reciprocating piston pump, having in combination two castings of generally semicylindrical shape each containing a cylinder, means for

120 securing the flat sides of said castings to each other to form a pump body, the flat side of each casting channelled so that when united said castings will form a suction chamber and a discharge chamber, a fluid

125 passage connecting each cylinder at each of its ends with the suction chamber, a valve in each of said passages opening away from the suction chamber, a fluid passage connecting each cylinder at each of its ends with the discharge chamber, a valve in each of said

130 passages opening toward the discharge chamber, a suction inlet connected with said suction chamber and a discharge outlet connected with said discharge chamber, a double acting piston for each cylinder, a connecting rod for each piston and unitary means for reciprocating said pistons, thru said connecting rods.

the suction chamber, a fluid passage connecting each cylinder at each of its ends with the discharge chamber, a valve in each of said passages opening toward the discharge chamber, a suction inlet connected with said suction chamber and a discharge outlet connected with said discharge chamber; a double acting piston for each cylinder, a crank shaft made of a plurality of parts so that each of the castings may have the pumping mechanism assembled therein com-

plete before the two castings are secured together, and means on the contiguous ends of said crank shaft sections when so assembled for so interlocking said sections that when the castings are bolted together both sections of the crank shaft will rotate together. 15

In testimony whereof I have hereunto set my hand.

LOUIS A. DOURSON.
